UNITED STATES PATENT OFFICE.

CHARLES R. BIRDSEY, OF HINSDALE, ILLINOIS.

PLASTER WALL BOARD.

Application filed October 10, 1921. Serial No. 506,676.

This invention relates to improvements in plaster wall boards and more particularly to the formation of the longitudinal edges thereof.

5 It is an object of this invention to produce a plaster board that may be readily used as a wall board, that is, a prepared board that may be secured to the studding of a building in the place of laths and then 10 plastered over before painting or papering or may be painted or papered after application without the necessity of first giving it a covering of plaster.

While the preferred form of this invention is illustrated upon the accompanying sheet or drawing, yet minor detail changes may be made without departing from the scope thereof.

In the drawings

20 Figure 1 is a view in cross-section of this improved plaster wallboard with parts broken away.

Figure 2 is a perspective view of Figure 1 illustrating the longitudinal and transverse 25 edges.

Figure 3 is a view illustrating in cross-section the adjoining edges of adjacent boards after application to a wall.

Figure 4 is a view similar to Figure 3 30 illustrating the application of a filling compound.

In carrying out this invention the plaster wallboard is formed with a composition body 1, preferably plaster, between cover sheets 35 2 and 3, preferably of paper. The longitudinal edges on each side are covered and protected by partially bending back each cover sheet upon itself so that the bent back portions 4 and 5 overlap or engage at their 40 ends, as shown in Figure 1, to hold the body from being forced out between the cover sheets or from exuding between the edges of the cover sheets during fabrication and assist in maintaining the board of uniform 45 thickness. It is preferable to score each cover sheet adjacent each longitudinal edge before passing it into the machine for making the board and then bending the margins at the edges partially back upon the body 50 of each sheet, along the scoring, as they pass through the machine, so that the board will be of uniform width.

The partial bending back of the margins at the edges of the cover sheets form a board 55 with a grooved edge, the scoring produces a board of uniform width, and the construc-

tion of the partially bent back margins at the edges insures uniform thickness along the longitudinal edges of the board. When used as a plaster board and nailed directly 60 to the studding 7 it is customary to leave a slight opening between the edges of the adjacent boards and the grooved edges will form pockets, such as 6 in Figure 3, into which the plaster covering will anchor and 65 bond the boards and the covering more firmly together. When used as a wallboard the edges being straight, the boards may be applied close together and nailed in place so that the boards may be painted or papered 70 and the edges being of the same thickness throughout as the body of the board, the applied boards will present an uninterrupted flat surface to receive the paint or paper. Also when used as a wallboard, in itself 75 presenting the finished wall without plastering over, the edges can be spaced slightly apart and the pocket 6 filled with a crack filling compound 8, as shown in Figure 4. This pocket 6 forming a key locked receptacle for holding the crack filler in place, so that it will present at all times a true flush face with the adjoining board.

What I claim is:

1. A plaster board having a composition 85 body and coverings on each side with the margins at the side edges of the coverings partially bent back upon themselves at an angle to each other to form grooved edges.

2. A plaster board having a composition 90 body and coverings on each side with the margins at the side edges of the coverings partially bent back upon themselves at an angle to each other and contacting with each other to form grooved edges.

3. A plaster board comprising a composition body and a covering on each side, said coverings being scored adjacent the margins of each longitudinal edge and the margins of each longitudinal edge partially bent 100 back upon themselves at an angle to each other along the scoring, producing a board of uniform width with grooved edges.

4. A plaster board having a composition body and coverings on each side with the 105 margins of the coverings at the side edges folded against the body and meeting at an angle to each other.

5. A plaster board comprising a plaster body and a cover sheet at each face side 110 thereof folded over an edge of said body to form a depression along said edge.

6. In a plaster board of the kind described and in combination, a plaster body and cover sheets at the face sides thereof, said sheets folded over and inwardly on the edge 5 of the body at an acute angle, the widths of the sheets being greater than the width of the body and sufficient to permit the folded-over portions to be brought together and substantially engage to provide a pronounced 10 groove at the edge of the board and entirely inclosing the plaster body.

7. A plaster board consisting of a plaster body provided with a covering inclosing the faces and opposite side edges, and having 15 a depression at each side edge.

8. The combination of a plurality of plaster boards arranged edge-to-edge, each having an edge groove at their juncture, of a key of suitable material inserted in said grooves for locking the parts against relative transverse movement. 20

9. The combination comprising a pair of plaster boards each consisting of a body of plaster enveloped by covering material, said boards being placed in substantially abutting relation and having recesses in their adjacent edges, a joint filler covering the joint between said boards and keyed within said recesses. 25
